UNITED STATES PATENT OFFICE.

JOHN BERG, OF GRINNELL, IOWA.

FIRE-EXTINGUISHER FOR CARS.

SPECIFICATION forming part of Letters Patent No. 229,854, dated July 13, 1880.

Application filed June 1, 1880. (No model.)

To all whom it may concern:

Be it known that I, JOHN BERG, of Grinnell, in the county of Poweshiek and State of Iowa, have invented certain Improvements in Fire-Extinguishers for Railway-Cars, of which the following is a specification.

My invention relates to that class of devices that are designed to be combined with a stove or car-heater in a car to prevent the dangers 10 and accidents and loss of life and property incident to the use of stoves and heaters in railway-cars.

Heretofore reservoirs filled with water have been connected with a stove in a car in such 15 a manner that when the car is thrown out of its normal level position on the track a valve that restrained the water would be automatically opened by force of gravity, to allow the water to escape from the reservoir and to deluge and extinguish the fire in the stove while the car inclined laterally relative to the track. My apparatus, patented April 6, 1880, No. 226,220, also provides for deluging the fire in the stove when a car becomes inverted or is 20 turned upon end, as frequently occurs in the breaking of bridges, by forming and combining a stand-pipe reservoir having a horizontal branch with a car and a stove or heater in such a manner that it will be operative whenever 25 the car is placed in any abnormal position whatsoever; but the automatic device used for opening a valve and flooding the fire was connected with the vertical portion of the stand-pipe only by means of a single conduit, 30 and incapable of emptying the reservoir completely or quickly.

The object of my improvement is to discharge the water more rapidly and completely; and my invention consists in connecting the 40 horizontal branch portion of the reservoir with the stove by means of vertical conduits, as hereinafter fully set forth.

The drawing represents a section of a car containing my improved apparatus, and illustrates its construction, application, and operation.

A is the main portion of my stand-pipe reservoir, fixed in a vertical position in the corner of the car. It may be cylindrical or angular, and formed in the wall of the car, or attached thereto in any suitable way. It is

preferably made of boiler-iron, and may vary in size, as desired.

B is a branch extending horizontally from the top portion of the vertical part A. C represents a stove or car-heater fixed to the car-floor in a position contiguous to the reservoir A and underneath its branch B. d is a horizontal tube connecting the reservoir with a vertical tube and the stove. f is a valve in 60 that end of the tube that enters the reservoir. g is a valve-stem that extends inward through the tube d. h is a lever pivoted to the tube and flexibly connected with the end of the stem inside of the tube to open and close the 65 valve. i is a spring attached to the upper end and long arm of the lever h in such a manner that it will, in its normal condition, exert its force to open the valve f. k is a tube extending from the top of the stove C to the 70 branch B of the stand-pipe reservoir. f' is a valve in its top end. It has a stem, g', the lower end of which is connected with a pivoted lever, h'.

h'' is a lever pivoted to the wall or other 75 suitable support in such a position relative to the lever h that its end bent downward at right angles will engage the top end of the said lever h. m is a cup-shaped platform composed of two distinct parts, one part of which 80 is rigidly connected with the upper end of the lever h' and the other part with the end of the lever h''. n is a ball-weight resting upon the sectional cup-shaped platform m in such a manner that its force of gravity will, when the car 85 is in a level and normal condition, be transmitted through the levers h h' h'' to the valves f and f' and hold them closed; and when the car is thrown into an abnormal position the ball will be displaced from the platform, and 90 the valves will be automatically opened, the one in the horizontal tube by means of the spring i and the one in the vertical tube by the pressure of the water in the branch B of the reservoir. By thus combining the vertical part of the reservoir and also the horizontal part with the stove two distinct valves in two distinct conduits are operated by means of one weight to allow the water to flow more rapidly into the stove, as required, to deluge 100 the fire when an accident occurs to throw the car into an abnormal position.

k' is a second vertical tube connected with the horizontal branch *B* of the stand-pipe reservoir and the stove *C* by means of the first vertical tube, *k*. *f''* is a valve in the top portion of the tube *k'*. *g''* is a valve-stem extending through the vertical tube. A cup-shaped platform at its top end retains a ball-weight to keep the valve closed by downward pressure as long as the car is in a normal position. A spring at the lower end of the stem opens the valve by upward pressure when the car is in an abnormal position and the ball-weight at the top of the stem is displaced. The ball-weights are secured by means of chains, so that they will readily return to their cup-shaped platforms when the car is returned to a level position on the track.

I claim as my invention—

1. The stand-pipe reservoir *A B*, the stove

or car-heater *C*, the horizontal tube *d*, having 20 valve *f*, the vertical tube *k*, having valve *f''*, the levers *h h' h''*, the spring *i*, the sectional cup-shaped platform *m*, and the ball-weight *n*, arranged and combined substantially as shown and described, to operate in the man- 25 ner set forth, for the purposes specified.

2. The reservoir *A B*, the stove or car-heater *C*, the vertical tubes *k* and *k'*, the valve *f''*, the stem *g''*, having a cup-shaped platform at its top to support a ball-weight, and lifting- 30 spring at its lower end, arranged and combined to operate substantially as and for the purposes shown and described.

JOHN BERG.
